CLOTHES HANGER SUPPORT ROD

Mark O. Uitz, Mountain View, Calif., assignor to
F.J.L. Corporation, Palo Alto, Calif.

Filed May 8, 1969, Ser. No. 17,083

Term of patent 14 years

Int. Cl. D6—01

U.S. Cl. D33—8

FIG. 1 is an isometric view of a clothes hanger support rod embodying my new design;

FIG. 2 is an end elevational view thereof;

FIG. 3 is a cross-sectional view taken along the line 3—3 of FIG. 1, with the end plate removed to illustrate the outer contour of the rod more clearly;

FIG. 4 is a front elevational view thereof; and

FIG. 5 is a bottom plan view thereof.

The design is characterized by the combination of a generally octagonal rod, circular end plates, and generally wedge shaped hanger brackets.

Both ends of the clothes hanger support rod are identical.

I claim:

The ornamental design for a clothes hanger support rod, as shown and described.
